(57) **CLAIM**

The ornamental design for an earring, as shown and described.

DESCRIPTION

FIG. 1 is a front and left side perspective view of an earring showing my new design:

FIG. 2 is a top front elevational view thereof:

FIG. 3 is a right side elevational view thereof:

FIG. 4 is a bottom plan view thereof; and,

FIG. 5 is a rear back view thereof.

A preferred embodiment of the earring is illustrated in FIG. 1 (front and left elevational view) and FIG. 2 (top view) and FIG. 3 (right side view) and FIG. 4 (bottom view) and FIG. 5 (back view) A round pupil taxidermy eye is adhered to a post bezel/cabochon setting style earring.

1 Claim, 1 Drawing Sheet

FIG. 1

FIG. 2

FIG. 3

FIG. 4

FIG. 5
